ATTORNEY

UNITED STATES PATENT OFFICE

DONALD PARKER, OF FRESNO, CALIFORNIA

AIR HEATER

Application filed February 23, 1929. Serial No. 342,014.

This invention relates to heating devices, the principal object being to provide an apparatus of this general character, especially designed and adapted for orchard heating which is so constructed as to obtain the maximum heating efficiency from a minimum amount of fuel; and so that the majority of the air as heated will be deflected downwardly and away from the heater. This is a desirable feature since air as heated naturally tends to rise and if too far above the ground at the outset, the practical value and utility of the heated air is largely nullified.

Though as stated, the heater is designed primarily for orchard heating during frosty weather, it is also suitable for indoor heating, as will be evident from the accompanying description.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of my heater as arranged for orchard use.

Fig. 2 is a top plan view of the heater.

Fig. 3 is a fragmentary enlarged section showing a flue pipe and an air deflecting plate associated therewith.

Fig. 4 is a diagrammatic vertical section showing the preferred arrangement of the air deflecting plates.

Referring now more particularly to the characters of reference on the drawings, the numeral 1 denotes a firebox to rest on or adjacent the ground and having air intake openings 2 of suitable character and size. A burner conventionally indicated at 3 is mounted centrally in the firebox. This burner for orchard use is of a type adapted to burn fuel oil, while for house or other interior use it would be of a type to burn gas. The necessary feed pipe 4 for the burner of course pro-

jects outwardly from the firebox to a necessary source of fuel supply (not shown).

The discharge or flue pipe 5 for the products of combustion from the burner projects upwardly from the firebox and a short distance above said box is arranged in the form of a coil 6 having any desired pitch and number of turns, which are spaced apart some distance from each other and terminate in an upwardly projecting stack or final discharge outlet 7. The flue and coil are preferably made of ordinary stove piping and fittings so that the coil is substantially in form as shown, with each side of a turn of the coil straight and set at a slope to the adjacent side.

Associated with such straight side of the coil and extending from end to end of said side is a horizontal deflecting plate 8, the ends of which are cut on an inward bevel from the outer to the inner edges of the plate. Each plate has a transverse concave curvature relative to the turn of the flue-coil thereunder, the inner edge of the plate being disposed inwardly of the inner side of the coil a considerable distance and being lower than the top of said turn and also lower than the outer edge of the plate, which latter edge is also some distance outwardly of the outer side of the coil.

The plates 8 being all horizontally disposed while the coil turns are sloping, each plate contacts with the straight length of the coil which it overhangs at one end, while being spaced from the same at the other end. The different plates 8 which are all separate from each other are therefore disposed in stepped relation, the end of one plate which contacts with its coil turn being overlapped somewhat by the plate of the adjacent coil turn at the end where the latter plate is spaced from its turn as indicated in Fig. 2.

Also, as will be particularly evident from Fig. 4, each set or layer of plates is so arranged that the central opening formed thereby is gradually decreased from bottom to top, so that at the topmost layer of plates, the vertical passage inside the coil is practically closed.

As a result of this air deflecting arrange-

ment air drawn up through the coil from between the firebox and the lower turn of the coil by the natural draft created by the heat from the products of combustion and 5 passing through the coil, is practically all trapped by the plates. This causes the air to be thrown outwardly over the tops of the different turns of the coil and it is then deflected downwardly and away from the immediate vicinity of the heater, due to the 10 curvature of the plates.

This not only prevents the air from going straight up to the top of the heater inside the area surrounded by the coil as would 15 otherwise be the case and where it would be largely wasted, but causes such air to come into contact with a larger portion of the area of the heated pipe than it otherwise would, thus more thoroughly heating the air. At the 20 same time the heated air as discharged from the heater is caused to be deposited close to the ground. This arrangement also causes the heated air to be discharged over a considerable area surrounding the heater.

25 To support the deflecting plates I provide rigid uprights 9 at the corners of the pipe coil, to which the ends of the various plates are connected, as shown in Fig. 3.

These uprights also support cradles 10 30 which project inwardly and support the coil at the bends or corners of the turns.

When used in an orchard some of the products of combustion from the burner may be discharged some distance away from the heater, as at points adjacent separated trees, by auxiliary flues 11 projecting at an upward slant from the main flue 5 between the firebox and coil. For interior use such auxiliary flues of course would be omitted.

40 From the foregoing description it will be readily seen that I have produced such a device as substantially fulfills the objects of the invention as set forth herein.

While this specification sets forth in detail 45 the present and preferred construction of the device, still in practice such deviations from such detail may be resorted to as do not form a departure from the spirit of the invention, as defined by the appended claims.

50 Having thus described my invention what I claim as new and useful and desire to secure by Letters Patent is:

1. An air heater including a firebox, a 55 source of heat therein, and a discharge flue projecting upwardly from the firebox in the form of a vertical helical coil exposed all around to the atmosphere, the turns of which are spaced from each other and from the firebox and means associated with the coil for causing air passing between the firebox and the coil and moving upwardly in the area included by said coil to be caught and deflected outwardly of the heater between the turns of the coil.

65 2. An air heater including a firebox, a

source of heat therein, a discharge flue projecting upwardly from the firebox in the form of a vertical helical coil exposed all around to the atmosphere, the turns of the coil being spaced from each other and from the firebox, and an air deflecting plate structure mounted in connection with the coil in spaced relation to and projecting between the turns thereof, said plates in cross section being curved concavely relative to the coil-turns therebelow and having their inner edges some distance inwardly of the coil and their outer edges some distance outwardly of the coil. 70 75

3. An air heater including a firebox, a source of heat therein, a discharge flue projecting upwardly from the firebox in the form of a vertical helical coil, the turns of the coil being spaced from each other and from the firebox, and are of substantially rectangular form, and horizontal air deflecting plates projecting between the turns of the coil, there being one such plate for each side of a coil-turn and the different plates being arranged in stepped relation; each plate being spaced at one end from the coil-turn immediately below and being arranged to catch air passing up in the area surrounded by the coil and deflect such air over the top of the corresponding coil-turn and then downwardly on the outside of the coil. 80 85 90 95

4. An air heater including a firebox, a source of heat therein, a discharge flue projecting upwardly from the firebox in the form of a vertical helical coil exposed all around to the atmosphere, the turns of the coil being spaced from each other and from the firebox, an air deflecting plate structure mounted in connection with the coil in spaced relation to and projecting between the turns thereof, said structure being arranged to catch air passing up in the area surrounded by the coil and deflect said air to the outside of the heater between the various turns of the coil. 100 105

5. A structure as in claim 2, in which the opening included between the inner edges of the plates at each turn of the coil is gradually decreased in size from bottom to top of the coil. 110

In testimony whereof I affix my signature.
